UNITED STATES PATENT OFFICE.

FRED ELMORE FARNHAM, OF RUMFORD, MAINE.

BAG-COUNTER FOR BAG-MAKING MACHINES.

1,057,629.

Specification of Letters Patent.

Patented Apr. 1, 1913.

Application filed May 18, 1911. Serial No. 627,938.

To all whom it may concern:

Be it known that I, FRED ELMORE FARNHAM, a citizen of the United States, and a resident of Rumford, in the county of Oxford and State of Maine, have invented 5 certain new and useful Improvements in Bag-Counters for Bag-Making Machines, of which the following is a specification.

My invention relates to devices for automatically counting the bags delivered from a bag-making machine, and has for its object the provision of a device that is actuated by the gearing of the bag-making machine and by working synchronously there- 15 with will at all times count the same number of bags, so that the packages of bags made up will be uniform as to number, size and weight.

My invention furthermore has for its object 20 the provision of two retainers for the bags as they are delivered from the machine, one of which is at all times in position to receive the finished bags from the machine, and the other out of position, so that the bags previously delivered thereto 25 may be removed therefrom by the operator to prepare it to receive the next lot of bags.

Another object of my invention consists 30 in the provision of an improved construction of delivering-rolls for the bag-machine operated by the actuating-shaft for the automatic counters by which said rolls are automatically positioned to deliver to the proper receptacle for receiving the finished 35 bags.

My invention will be described herein- 40 after and illustrated in the accompanying drawings, in which—

Figure 1 is a side view of a conventional 45 delivering device for a bag-making machine, showing my improved counter in position, the counter being in position to load the uppermost receptacle; Fig. 2, a similar view of the bag-counter and de- 50 liver-rolls, only, showing the lowermost receptacle in position to receive the bags; Fig. 3, a side view of the opposite side of the counter and delivery-rolls, showing the parts in the position shown in Fig. 1; Fig. 50 4, a view of the same parts shown in Fig. 3, with the parts in position shown in Fig. 2; and Fig. 5, a view of the lower portion of the counter, showing the parts in the same position as in Fig. 1.

55 In the drawings similar reference char-

acters will be used to designate all the parts that correspond in the several views.

A indicates the delivery device of a bag-making machine, consisting of drums B, C, and D, suitably journaled on standards E, 60 and guide-rolls G, H, I and J, likewise journaled on uprights E, and delivery-rolls 1 and 2, journaled on arms 3 and 4, pivotally secured to said uprights E.

K indicates a conveyer-belt extending 65 from the bag-making machine (not shown) and engaging drums B, C and D, delivery-roll 1, and guide-roll G, H, and I, while L indicates a short belt doubling with belt K over drums B, C, and D, then engaging 70 delivery-roll 2 and guide-roll J, the two belts operating to inclose the bags carried from the machine (not shown), while passing over drums B, C, and D to elevate them 75 into position to be delivered to my counting device.

5 indicates an upright frame secured adjacent to the upright E, on which is journaled a shaft 6, that is geared to the bag-machine by any suitable gearing, so that it 80 is rotated synchronously therewith.

7 indicates a beam slidably mounted in a slotted plate 8, secured to frame 5, on which is rigidly secured boxes 9 and 10, positioned 85 to receive bags delivered from the delivery device heretofore described, being opposite the delivery-rolls 1 and 2.

11 indicates a cam-disk secured for rotation to shaft 6, one-half of the disk being concentric with the shaft, as shown at 12, while the other part of the disk is formed on an outwardly-extending spiral, as shown at 13, ending with a radial shoulder 14, connecting the widest part of the spiral 13 with the beginning of the concentric portion 12. 90 By this mechanism, assuming that the foot of beam 7 is resting on the part 12 abutting shoulder 14 at the beginning of the rotation of the shaft, it will be apparent that the uppermost box 9 will be in position to receive bags from the delivery device and will remain in said position during one-half of the rotation of the disk, and that when the spiral portion 13 of the disk engages the foot of the beam that it will be elevated to bring the lowermost box 10 into position to receive the bags. While the lowermost box 10 is receiving the bags, the uppermost box 9 will be emptied by an attendant, and when the disk 11 has rotated so that the lower end 100 105 110

of the beam drops off of the spiral 13 onto the concentric portion 12 the uppermost box 5 will be returned to its original position and receive the bags, while the lowermost box 5 will be emptied. As the two portions 12 and 13 of the disk 11 engage the beam 7 through the same length of period of rotation of the shaft, it will be apparent that the same number of bags will be deposited 10 in each box. Furthermore it will be apparent that the speed of shaft 5 may be regulated as desired relatively to the speed of the operation of the bag-making machine, so that the number of bags deposited in the 15 boxes may be fixed, as desired.

15 indicates a rod slidably mounted in guide-brackets 16, secured to frame 5, 17 a bell-crank lever pivotally secured to said frame 5 and having one arm pivotally secured to the upper end of rod 15 and its other arm provided with a series of holes 18.

19 indicates an extension of arm 3, and 20 a link connecting extension 19 and the free arm of lever 17 being pivotally secured in 25 one of the holes 18.

21 designates a cam-disk secured to shaft 6 and positioned to engage the lower end of rod 15, said disk having one-half of its circumference cut on a spiral, as shown at 22, 30 and the remainder cut, as shown at 23, concentrically with the shaft 6, and ending with a radial shoulder 24, connecting the end of said concentric portion with the narrowest portion of the spiral.

35 It will be apparent that while the lower end of the rod 15 engages the spiral portion 22 the rod will be gradually raised and the angle of the delivery-rolls 1 and 2 to the perpendicular shifted, so that the bags delivered therefrom will be emitted on planes gradually approaching and finally reaching the horizontal; and that the horizontal emission of the bags will continue through 40 one-half of the rotation of the shaft. Furthermore it will be apparent from the drawings that the positions of the two disks are so arranged that while the beam 7 is engaging the concentric portion 12 of the disk 11 to fill the uppermost box 9 the rod 15 is

45 engaging the concentric portion 23 of disk 21, and that when the disk 11 is rotated so that the beam is engaged by the spiral portion of the disk, the rod 15 will drop off of

the end of concentric portion 23 at the shoulder 24, and the delivery-rolls will incline downwardly to deliver into the lowermost box 10, and as the box is gradually elevated, as hereinbefore described, the angle of the rolls will be gradually returned to the perpendicular to insure delivery into said 60 box 10.

25 indicates a spring secured to rod 15 and frame 5, normally tending to actuate said rod downwardly and operating to hold the rod in engagement with the periphery 65 of the disk at all times.

Having thus described my invention, what I claim is—

1. In combination with the delivery mechanism of a bag-machine, arms pivotally secured thereto, delivery-rolls journaled on said arms, one of said arms being provided with an extension, a bell-crank lever, a link connecting one arm of said lever with the extended end of the arm aforesaid, a rod 70 slidably mounted and secured to the free arm of the bell-crank lever aforesaid, and a cam-disk engaging said rod, one portion of the periphery of the disk being spirally arranged, and the remainder of the periphery 80 of the disk being equally distant from the center thereof, substantially as shown and described.

2. In combination with the delivery mechanism of a bag-machine, arms pivotally secured thereto, delivery-rolls journaled on said arms, one of said arms being provided with an extension, a bell-crank lever, a link connecting one arm of said lever with the extended end of the arm aforesaid, a rod 85 slidably mounted and secured to the free arm of the bell-crank lever aforesaid, means to actuate said rod, a vertically disposed beam slidably mounted, superposed boxes secured to said beam and positioned 90 to receive bags delivered by said rolls, and means to actuate said beam to adjust the boxes alternately in position to receive the bags, substantially as shown and described.

In witness whereof, I have hereunto 100 signed my name in presence of two subscribing witnesses.

FRED ELMORE FARNHAM.
